UNITED STATES PATENT OFFICE.

ELIZABETH P. WHITE, OF SALISBURY, NORTH CAROLINA.

SCRUB-APRON.

1,004,717.

Specification of Letters Patent.

Patented Oct. 3, 1911.

Application filed August 3, 1910. Serial No. 575,331.

To all whom it may concern:

Be it known that I, ELIZABETH P. WHITE, a citizen of the United States, residing at Salisbury, in the county of Rowan and State 5 of North Carolina, have invented certain new and useful Improvements in Scrub-Aprons, of which the following is a specification.

This invention relates to aprons designed 10 to be used by persons while scrubbing or when required to assume a kneeling posture, and one of the principal objects of the same is to provide an apron having a soft pad secured to the inner side thereof to prevent 15 injury to the knees of the wearer while kneeling upon the floor in scrubbing or house cleaning.

Another object of the invention is to provide 20 an apron of water proof material having a pad secured to the inner surface thereof, said pad being formed of felt or other soft material and extending across the apron in line with the knees of the wearer.

These and other objects may be attained 25 by means of the construction illustrated in the accompanying drawing, in which,

Figure 1 is a perspective view of a scrub 30 apron made in accordance with my invention. Fig. 2 is a transverse sectional view of the same, taken through the apron and pad.

Referring to the drawing the numeral 1 35 designates an apron made of thin water proof material like oil cloth, said apron being provided with a waist band 2 having

a series of button holes 3 on one end thereof and a button 4 on the opposite end thereof. Other fastening means may be substituted however for the button and button holes.

Secured to the inner side of the apron 1 40 is a pad 5 of felt or other similar material, said pad being preferably secured by stitches to the body of the apron in line with the knees of the wearer. The pad 5 is preferably 45 of rectangular form and is sufficiently flexible to conform to the shape of the apron when placed upon the wearer, said pad preferably extending across the apron a sufficient length to insure contact of the knees with the pad when in use.

My invention is of simple construction, 50 can be manufactured at low cost and will permit free use of the limbs during the scrubbing operation.

I claim:

The herein described scrub apron made 55 from a piece of water-proof fabric, said apron being provided with an adjustable waist-band and a felt pad in the form of a strip secured to the inner surface of the apron, said pad extending entirely across 60 the apron in line with the knees of the wearer and said apron extending below said pad for the purpose described.

In testimony whereof I affix my signature in presence of two witnesses.

ELIZABETH P. WHITE.

Witnesses:
